DESIGN FOR A TOY WATER GUN

William E. Braham, Los Angeles, Calif.

Application July 29, 1946, Serial No. 132,090

Term of patent 3½ years

(CL. D34—15)

To all whom it may concern:

Be it known that I, William E. Braham, a citizen of the United States of America, residing in the city of Los Angeles, in the county of Los Angeles, State of California, have invented a new, original, and ornamental Design for a Toy Water Gun, of which the following is a specification, reference being had to the accompanying drawings, forming a part thereof.

Figure 1 is a plan view of the toy water gun of my novel design;

Figure 2 is a side elevational view of my toy water gun; and

Figure 3 is a front elevational view of the gun as seen from the muzzle end.

I claim:

The ornamental design for a toy water gun, substantially as shown.

WILLIAM E. BRAHAM.
